UNITED STATES PATENT OFFICE.

WILHELMINA MAC WATTERS LOWRIE, OF BUFFALO, NEW YORK.

DESIGN FOR A SKIRT-SUPPORTER.

SPECIFICATION forming part of Design No. 34,022, dated February 5, 1901.

Application filed January 11, 1901. Serial No. 42,931. Term of patent 7 years.

To all whom it may concern:

Be it known that I, WILHELMINA MAC WATTERS LOWRIE, a citizen of the United States, and a resident of Buffalo, in the county of Erie and State of New York, have invented and produced a new and original Design for a Skirt-Supporter, of which the following is a specification, reference being had to the accompanying drawings, forming a part thereof, in which—

Figure 1 is a front elevation of a skirt-supporter embodying the features of my design, and Fig. 2 is an edge view of the same.

The leading features of the design consist in the head A, which at the upper portion of each side is provided with arms B, terminating at their upper ends in hooks C, which hooks are directed downward at the front of the head and in direction of its side edges, together with an arm D intermediate of the side arms, which intermediate arm terminates in a hook E', extending downward at the front of the head.

Another leading feature of the design consists in a central opening E in the head below 25 the intermediate arm D and a downwardly-extending hook D', which appears integral with the lower wall of the opening E at the front of the head.

The minor features of the design consist 30 in the shank F, which constitutes a continuation of the head, and in the longitudinally-arranged openings F' in the shank.

Having thus described my invention, I claim as new and desire to secure by Letters 35 Patent—

The design for a skirt-supporter herein shown and described.

In testimony whereof I have signed my name to this specification in the presence of 40 two subscribing witnesses.

WILHELMINA MAC WATTERS LOWRIE.
